TOWER SCALE FRONT PANEL

Glenn W. Tamm, Park Ridge, Ill., assignor to
U. S. Slicing Machine Company, Inc., La Porte,
Ind., a corporation of Indiana

Application May 29, 1951, Serial No. 15,339

Term of patent 14 years

(Cl. D52—10)

To all whom it may concern:

Be it known that I, Glenn W. Tamm, a citizen of the United States and a resident of Park Ridge, in the county of Cook and State of Illinois, have invented a new, original, and ornamental Design for Tower Scale Front Panel, of which the following is a specification, reference being had to the accompanying drawings, forming a part thereof.

Fig. 1 is an elevational view illustrating the front or operator's side of a tower scale front panel, showing my new design;

Fig. 2 is a side view of the tower scale front panel shown in Fig. 1;

Fig. 3 is an elevational view illustrating the front or operator's side of the tower scale front panel in a position which is inverted with respect to the position shown in Fig. 1; and

Fig. 4 is a side view of the tower scale front panel shown in Fig. 3.

The broken line showing is for illustrative purposes only.

I claim:

The ornamental design for a tower scale front panel, as shown and described.

GLENN W. TAMMEN.
